No. 819,253.

PATENTED MAY 1, 1906.
H. M. REYNOLDS & W. E. SHERWOOD,
MOP WRINGER,
APPLICATION FILED APR. 28, 1904.

UNITED STATES PATENT OFFICE.

HERMAN M. REYNOLDS AND WILLIAM E. SHERWOOD, OF ONEIDA, NEW YORK, ASSIGNORS, BY DIRECT AND MESNE ASSIGNMENTS, TO THE WHITE MOP WRINGER COMPANY, OF FULTONVILLE, NEW YORK.

MOP-WRINGER.

No. 819,253.

Specification of Letters Patent.

Patented May 1, 1906.

Application filed April 28, 1904. Serial No. 205,333.

To all whom it may concern:

Be it known that we, HERMAN M. REYNOLDS and WILLIAM E. SHERWOOD, of Oneida, in the county of Madison, in the State of New York, have invented new and useful Improvements in Mop-Wringers, of which the following, taken in connection with the accompanying drawings, is a full, clear, and exact description.

This invention relates to the class of mop-wringers in which a presser-board is connected to the wringer-frame and adapted to be moved toward a stationary breast attached to the wringer-frame to express the water from the mop introduced between said presser-board and breast; and the invention consists in improved constructions of the component parts of the mop-wringer, which is thereby rendered very efficient and convenient in its operation, as hereinafter described, and as illustrated in the annexed drawings, in which—

Figure 1 is a front elevation of a mop-wringer embodying our invention. Fig. 2 is a vertical transverse section on the line W W in Fig. 1. Figs. 3, 4, and 5 are transverse sectional views on the lines X X, Y Y, and Z Z, respectively, in Fig. 2. Fig. 6 is a detail inner face view of a portion of one of the side walls of the wringer-frame, and Fig. 7 is a detail inner side view of a portion of one of the arms to which the presser-board is attached.

Similar letters of reference indicate corresponding parts.

A A denote two vertical plates which are disposed parallel and constitute side walls of the stationary wringer-frame, each of which walls is formed with a hook a, by which the wringer-frame is hung on the top of the mop-pail P. To brace the portions of the pail on which the wringer is hung, as aforesaid, we form each of the side walls A with a straight downwardly-extending shank a', which is disposed adjacent to the hook a and bears with its entire length on the inner side of the pail directly opposite the hook, as shown in Fig. 2 of the drawings. The said shank is widened and convexed transversely to stiffen it and at the same time provide it with a broad convex bearing a'', corresponding to the

curve of the inner side of the pail throughout the length of the shank, and thus securely support the wringer and obviate undue abrasion of the portion of the pail which is in contact with the shank a'. Each of said shanks is formed at its lower end with an ear a³, projecting inwardly from it at right angles to the shank.

The walls A A of the wringer-frame are provided with slots c c or other suitable openings for escape of the expressed water. Each of the said walls is formed with parallel flanges or ribs b² b², extending from the top to the bottom of the inner edge of the wall, and with a bracket c', disposed beneath the wall and extending from the flanges b² b² part way the width of the wall. The inner side of said bracket is provided with parallel ribs c² c², extending lengthwise of the bracket and to the lower ends of the flanges b² b², as shown in Figs. 2 and 6 of the drawings. Between these upright ribs b² b² are inserted the side edges of the breast B, consisting of a board or plate which is perforated for escape of the water expressed from the mop.

The outer surface of the breast B is provided with a horizontal groove d, in which is embedded a rod e, which is formed at one end with a conical head e', countersunk in one of the side walls of the frame and provided on its other end with a nut e², and serves to tie said walls to each other and retain the breast B in the frame. The end portions of the rod e engage recesses e³ e³, provided in the outer ribs of the walls, as more clearly shown in Fig. 2 of the drawings.

C represents the presser-board, which is movable toward and from the stationary breast B and serves to express the water from the mop introduced between them. This presser-board is carried on the upper portions of vertical arms D D, which are pivoted at their lower ends to the aforesaid ears a³ a³, projecting from the corresponding ends of the shanks a' of the wringer-frame, as indicated at b³. The upper portions of the arms D D are each provided on the inner side with a pair of longitudinal parallel flanges f f, one of the flanges of each pair terminating at its lower end with a shoulder f'. The said presser-board is perforated for escape of the water

expressed from the mop, and it is inserted with its side edges between the flanges $f f$ of the arms $D D$ and is sustained in its position by means of a transverse rod f^2 , embedded in 5 a groove f^3 in the outer face of the presser-board substantially like the aforesaid rod e . Said rod f^2 is fastened at its ends to the arms $D D$ and firmly ties said arms together.

h denotes the bottom board or plate which 10 extends from the base of the breast B and is disposed to allow the presser-board C to pass over it and is arranged with water-passages between it and the said breast and presser-board, as indicated at $g g$ in Fig. 2 of the 15 drawings. This bottom board is inserted with its end edges between the rib extensions $c^2 c^2$ on the brackets $c' c'$, formed on the wringer-frame, and through these brackets pass screws entering the ends of the bottom 20 board, whereby the latter is held stationary on the frame and supported independently of the presser-board and breast, and thus adapted to be readily placed in position without requiring special fitting to either the 25 presser-board or breast. The most important features of said support for the bottom board h are the rigidity of brackets $c' c'$ and the bearings of the flanges $c^2 c^2$ of said brackets engaging the top and bottom of the board, 30 so as to prevent it from splitting in the operation of the wringer.

The presser-board C receives motion from a rock-shaft k , which is mounted at its ends in the side walls $A A$ of the wringer-frame 35 and has affixed to it a handle or lever L , by means of which the operator imparts motion to said rock-shaft. This rock-shaft has rigidly projecting from it two sectoral gears m , disposed, preferably, near the inner faces of 40 the side walls of the frame and engaging similar sectoral gears n , formed on the free ends of the arms or connecting-rods n' , pivoted at their opposite ends to ears $n^2 n^2$, projecting outwardly from the outer flanges $f f$ of the 45 arms $D D$, as clearly shown in Fig. 2 of the drawings.

By means of links or straps l , connected at their ends to the gears $m n$, the said gears are maintained in engagement, as shown in Figs. 50 1 and 2 of the drawings.

By placing the gears m eccentric on the shaft k , as shown in Fig. 2 of the drawings, the pressure transmitted to the presser-board C is gradually increased during the operation 55 of the lever L in squeezing the mop introduced between said presser-board and opposed breast B , and thus the described mop-wringer is rendered more efficient in its operation.

In order to insure the return of the water 60 issuing through the perforations of the presser-board C to the mop-pail and at the same time protect the operator, we employ a water shed or shield r , which is applied to the outer face of the presser-board and extends across 65 the entire perforated portion of said board

and to the base thereof with a space between them to conduct the expelled water down on the exterior of the presser-board and to the bottom board h , from whence said water passes through the adjacent passage q to the 70 interior of the mop-pail. This shield consists, preferably, of an imperforate metallic plate, which is formed at its side edges with flanges $r' r'$, which are inserted between the 75 edge portions of the presser-board and lugs $s s$, projecting from the outer flanges $f f$ of the arms $D D$, the bottom edges of which flanges rest upon the aforesaid shoulders $f' f'$ of said flanges, as shown in Figs. 1 and 3 of the drawings. 80

One of the important features of our invention, which will be readily observed, resides in the attaching of the bottom board to the wringer-frame independent of the breast and presser-board and in arranging the bottom 85 board with passages between it and the bases of the presser-board and breast, which passages permit a free egress of the expressed water at both the rear and front edges of the said bottom board, and, furthermore, by providing the bottom board with rigid supports extending across the greater portion of the width of its end portions the board effectively resists the strain of the pressure of the 90 mop thereon incident to the squeezing of the 95 mop between the presser-board and breast.

Another feature of our invention resides in the employment of a removable shield arranged at the outer face of the presser-board, which shield serves to conduct the water issuing through the perforations of the presser-board into the mop-pail, and thereby prevent the water from coming in contact with the person operating the wringer. The detachability of the shield permits convenient access to the rear of the presser-board for cleaning the board when required. 100

By forming the shanks a' with the convex bearings a^2 extending the entire length of the shanks, as hereinbefore described, we 105 strengthen said shanks and obviate wear and abrasion of the inner side of the pail incident to the contact of the shanks with said part of the pail.

Having described our invention, what we 115 claim is—

1. The combination, with the stationary wringer-frame, stationary breast and the presser-board provided with perforations for escape of the expelled water, of a water-shed 120 disposed across the exterior of the entire perforated portion of the presser-board and leading to the interior of the mop-pail, as set forth.

2. The combination, with the wringer-frame, the stationary breast and the perforated presser-board, of the bottom board secured stationary to the wringer-frame and disposed with a water-passage between it and the bottom of the presser-board, and a water-shed extending completely across the perfo- 125 130

rated portion of the presser-board and leading to the bottom board adjacent to the aforesaid water-passage as set forth.

3. In a mop-wringer of the within-described class, the combination with the perforated presser-board, of a water-shed fastened to the exterior of said presser-board and extending across the entire perforated portion thereof with a space between them and leading to the interior of the mop-pail.

4. The combination in a mop-wringer of a movable presser, a stationary breast, a frame supporting the breast, a rock-shaft mounted in bearings in the frame, a gear-sector on the shaft, a link connected with the movable presser having a gear-sector meshing with the gear-sector on the shaft, and means for holding said gear-sectors in working engagement, substantially as set forth.

5. The combination of the wringer-frame, stationary breast, and stationary bottom board, a pair of vertical arms pivoted to the frame, the presser-board secured to said arms, a shield disposed across the exterior of the perforated portion of the presser-board with a space between them and leading to the interior of the mop-pail, and means securing the said shield to the presser-board.

6. The combination of the wringer-frame, the stationary breast, the stationary bottom board, a pair of vertical arms pivoted to the frame, the presser-board secured to said arms, and a shielding-plate disposed at the outer face of the presser-board and formed at its side edges with flanges secured between the presser-board and arms as set forth and shown.

7. The combination with the wringer-frame, of a pair of vertical arms pivoted to said frame and formed with parallel inwardly-projecting flanges, the presser-board secured at its side edges between said flanges, and a shielding-plate formed at its side edges with

flanges secured between the presser-board and outer flanges of the said arms as set forth 45 and shown.

8. The combination with the wringer-frame, of a pair of vertical arms pivoted to said frame and each formed with a pair of parallel inwardly-projecting flanges, the outer 50 flanges terminating at their lower ends with shoulders, and formed at their main portions with lugs disposed out of the plane of the flanges, the presser-board inserted with its side edges between said flanges and secured 55 therein, and a shielding-plate disposed at the outer face of the presser-board and formed at its side edges with flanges inserted between the aforesaid lugs and presser-board and supported on said shoulders as set forth and 60 shown.

9. The combination with the wringer-frame, a pair of vertical arms pivoted to said frame, a presser-board secured to said arms, and a rock-shaft mounted in opposite sides of 65 the frame, of sectoral gears projecting eccentric from the rock-shaft, arms pivoted to the arms of the presser-board and formed with sectoral gears engaging the gears of the rock-shaft, and straps or links coupling said gears 70 together as set forth and shown.

10. The combination in a mop-wringer of a movable presser, a stationary breast, a frame supporting the breast, a rock-shaft mounted in bearings in the frame, an eccentric gear-sector on the shaft, a connecting-rod having teeth engaging the gear-sector, and means for holding the teeth of the connecting-rod and gear-sector in mesh, substantially as set forth.
